UNITED STATES PATENT OFFICE.

CHENEY A. MCEACHERON, OF GRAND RAPIDS, MICHIGAN, ASSIGNOR TO ALABASTINE COMPANY, OF GRAND RAPIDS, MICHIGAN, A CORPORATION OF MICHIGAN.

PRINTING MECHANISM.

Application filed April 3, 1922. Serial No. 549,115.

To all whom it may concern:

Be it known that I, CHENEY A. MCEACHERON, a citizen of the United States of America, residing at Grand Rapids, in the county of Kent and State of Michigan, have invented certain new and useful Improvements in Printing Mechanism; and I do hereby declare the following to be a full, clear, and exact description of the invention, such as will enable others skilled in the art to which it appertains to make and use the same.

This invention relates to a printing mechanism, by means of which several colors of a wall coating or finishing compound may be applied to paper to represent what has been termed, "opaline" effects, that is, the appearance which a wall will have if the same is repeatedly touched with a brush at closely adjacent spots, the brush being supplied with the compound to be transferred to the wall, different colors of the compound being applied in the same manner one after the other. The printing mechanism which I have invented is for the printing of sheets of paper with the actual wall finishing compound for use in advertising the same, and I have used it particularly in the application of alabastine wall coverings to said paper for magazine advertising, though it is apparent that the use of the invention is in no-wise thus limited. It is a primary object and purpose of the invention to provide a mechanism and process of printing by means of which the above stated ends may be attained, and the printing done with great rapidity, two or more of the colors being applied so as to obtain the "opaline" effect. A further object of the invention is to make a mechanism of this kind, and equip it with many novel features of construction for the effective printing of the paper as outlined, mechanism being supplied for feeding the material that is needed in printing, and more particularly, equipping the machine with an exceptionally serviceable printing roller which automatically applies the compound to the paper in similitude to the brush touching process noted. These and many other novel features will appear as understanding of the invention is had from the following description, taken in connection with the accompanying drawings, in which,

Fig. 1 is a longitudinal vertical section taken through one end of the machine.

Fig. 2 is a like section through the opposite end thereof.

Fig. 3 is an enlarged vertical section taken transversely through the machine at the point where one of the printing rollers is mounted.

Fig. 4 is a fragmentary enlarged vertical section taken longitudinally of the machine at said printing roller.

Fig. 5 is a fragmentary horizontal section taken substantially on the plane of line 5-5, of Fig. 3.

Fig. 6 is an elevation looking at one side of the machine at one end thereof, and showing the means used for turning the printing and transfer rollers, and for operating the feeding mechanism, parts being broken away to better disclose the structure, and

Fig. 7 is a fragmentary side elevation showing the mountings for the several rollers.

Like reference characters refer to like parts in the several figures of the drawings.

In the construction of the machine, an elongated table 1 is used of any required width, being carried on an under frame 2 which is supported by a plurality of posts 3 and 4. Posts 4 are wider than posts 3 and extend above the table, each being divided above the table to make a vertical slot between the parts 4^a, the purpose of which will later appear. Rollers 5 and 6 are mounted horizontally at opposite ends of the table, and an endless belt 7 passes over the table, around the rollers, and under the table as shown. The table at a number of points in its length has a portion removed leaving wide slots or openings the full width thereof, said openings occurring wherever the posts 4 are used. The construction illustrated shows but two of such openings but, if desired, the number may be increased. Rollers 9 and 10 are mounted horizontally between the pairs of posts 4, the upper sides of such rollers lying in the same plane with the upper side of the table. The belt 7 runs over the rollers 9 and 10 as shown.

A platform 11 is carried on posts 3 at one end of the machine and under the table (see Fig. 2), on which an electric motor 12 is supported. It drives suitable reduction gearing and other mechanism, indicated at 13, to in turn drive a chain 14 which passes around a sprocket wheel 15 secured to one

end of the shaft 6^a of roller 6, thus driving the roller and operating the belt at uniform speed.

The shaft 10^a on which roller 10 is mounted at one end is equipped with two chain wheels 16 and 17 and at its opposite end with a drum 18 in which a cam groove 19 is cut. The same construction is applied to the shaft of roller 9, except that the wheel 17 is left off. In fact the structure shown in Fig. 3, with this one exception, is identical with that above the roller 9, and a description for one will suffice for both. Directly over the roller 10 a printing roller 20 is horizontally mounted, being covered with a natural sponge covering, shown at 21. The sponge has cavities and openings more or less irregularly placed throughout its entire surface, and is of a soft yielding nature, making it particularly applicable for the use I have found for it in printing, especially as it is an exceptionally good absorbent of wall coatings dissolved in water, such as alabastine and similar products. The printing roller is carried on a shaft 22, the ends of which have bearings in journal boxes 23 freely mounted in the vertical slots in posts 4, heretofore described. One end of shaft 22 is extended through its journal and equipped with three chain wheels 24, 25 and 26, as seen in Fig. 3.

A transfer roller 27 on a shaft 28, mounted in journal boxes 29 is located over the printing roller in contact engagement therewith. The shaft 28 is likewise extended at one end and equipped with a chain wheel 30. A second transfer roller 31 on shaft 32, mounted in boxes 33 lies above and in engagement with roller 27. A fourth transfer roller 34, on a shaft 35 passing through journal boxes 36 lies above and in contact with the roller 31. All of the journal boxes are freely received in the slots in the upper portions of posts 4. One end of the shaft 35, at the side of the machine opposite to that at which the different chain wheels described are located is equipped with a collar 37 with which the upper end of a lever 38 pivotally mounted between its ends on a bracket 39 engages, the lower end of the lever having means entered into the cam groove 19 of drum 18. It is evident that with the rotation of roller 10, a reciprocatory movement is given to the roller 34, the same being moved back and forth over the roller 31 below. All of the transfer rollers have solid cores covered with a fabric covering, which may be felt, or any other equivalent material.

Between two brackets 40 secured at the upper ends of posts 4, a trough like container 41 for the material used is located directly over the roller 34. At the under side of the trough, a cylindrical member 42 is located, having a plurality of spaced apart

holes 43 in its upper and lower sides opposite each other, a rod 44 being located lengthwise of the member 42 and having transverse openings 45 therethrough which are periodically brought into registry with the holes 43. A shaft 46 extends from the rod 44, passing through a suitable stuffing box 47 which precludes escape of the liquid, said shaft at its outer end being equipped with a chain wheel 48. A shaft 49 is mounted lengthwise of the container 41 on which a plurality of tufts of brush bristles 50 are secured, as shown, which serve to keep the material stirred and the openings 43 at the upper side of member 42 unobstructed. Shaft 49 is extended at one end and equipped with a chain wheel 51.

An endless chain 52 passes around the wheels 25 and 48. A second chain 53 passes around the wheels 26 and 51. A second chain wheel 54 is fixed to the roller shaft 6^a (see Fig. 6) for driving an endless chain 55 which passes over wheel 30, thence downwardly against the opposite side of wheel 24 and then around wheel 16. It is evident that wheels 30 and 16 and their associated rollers are driven in the same direction and the wheel 24 and the printing roller in the opposite direction. A chain 56 is driven by wheel 17 and leads to the corresponding wheels 30, 24 and 16 of the printing construction associated with the roller 9 for driving the same.

An elongated sheet metal cover or casing 57 is placed over the table beyond the printing devices, across the upper portions of which a number of transverse burners 58 are located, for the burning of gaseous fuel. A protecting plate and deflector 59 is placed under each burner to protect the belt and sheets of paper 60 passing thereunder and more or less evenly disseminate the heat throughout the space under the casings.

With a construction as described, the sheets of paper are laid on to the conveying belt 7 at the end of the machine where roller 5 is mounted, the sheets being successively carried by the belt under the first printing roller 20 from which one color of alabastine is printed on to the paper. It will be evident that the mixed alabastine and water in the trough container 41 is fed by gravity periodically through the openings 43 and 45 onto the transfer roller 34 from which it is transferred through rollers 31 and 27 to the natural sponge covering of roller 20. This sponge coming against the paper prints the same wherever there is contact but leaves the paper blank at the openings and depressions in the sponge. The sheet printed with the one color then passes under the first casing 57 and the water is dried so that when the second printing mechanism is reached, it is in shape to pass therethrough to receive another color. While I have shown

but two of the printing devices in the machine, it is apparent that the number may be increased if more colors are to be printed. After the second printing, the sheet passes 5 under the second casing 57 and is dried so that when it passes to the end of the machine it is ready to be placed in a pile with the others previously printed.

This machine is in practical use and has 10 proven exceptionally satisfactory. With it, sheets of paper may be fed rapidly through the printing devices, receive a similitude of brush impressions of one color, be dried, and then receive impressions of a different color, 15 followed by a drying of the sheet so that it is immediately ready for any further operations, such as cutting to size, packing and shipping, or the like. The invention is defined in the claims appended hereto and 20 comprises all forms of construction and variations in constructive detail or method of operation that are comprehended by said claims.

I claim:

- 25 1. In a machine of the character described, an endless carrying belt located substantially horizontal, means to drive the same, a plurality of spaced apart printing rollers located over the belt to print sheets carried thereunder by the belt, and elongated drying means located over the belt beyond each printing roller, substantially as described.
2. In a machine of the character described, an endless carrying belt, printing rollers having absorbent coverings thereto located over the belt to bear against sheets carried under said rollers by the belt, transfer rollers located above and in contact engagement with said coverings, and drying apparatus located over the belts to which the sheets are carried after receiving impressions from the printing rollers.
3. In a machine of the class described, an 45 elongated container for holding wall covering dissolved in water, a cylindrical mem-

ber located lengthwise of and under the container, said container and member having aligned openings therethrough, a rod filling the member and having openings therethrough adapted to come into conjunction with the openings in the container and member, transfer rollers mounted below said container in position to receive the contents of the container passed through said openings, a printing roller below and in contact engagement with the transfer rollers, means for rotating the printing roller, means for rotating the transfer rollers, and means for rotating said rod, substantially as described. 60

4. A machine containing the elements in combination defined in claim 3, combined with means for reciprocating the uppermost transfer roller simultaneously with the rotation of the remaining rollers. 65

5. In a machine of the class described, an endless carrying belt located substantially horizontal, printing rollers having absorbent coverings located over the belt to bear against sheets carried under the rollers by 70 the belt, said printing rollers being located considerable distances apart, and drying apparatus located over the belts under which the sheets are carried after receiving impressions from the printing rollers, said apparatus being located beyond each printing roller. 75

6. In a machine of the class described, an endless carrying belt located substantially horizontal, printing rollers having absorbent coverings located over the belt to bear against sheets carried under the rollers by the belt, said printing rollers being located considerable distances apart, an elongated inverted sheet metal pan serving as a covering or housing located over the belt beyond each printing roller, and means to supply heat to the air under said pans or coverings, substantially as described. 80

In testimony whereof I affix my signature.

CHENEY A. McEACHRON.
